COMBINATION SPOTTING SCOPE, CARRYING CASE AND STOCK THEREFOR

Donald J. Burris, Aurora, Colo., assignor to Redfield Co., Denver, Colo.

Filed May 6, 1970, Ser. No. 22,840

Term of patent 14 years

Int. Cl. D16—08; D3—01

U.S. Cl. D57—1

FIG. 3.

FIG. 4.

FIG. 5.

FIG. 6.

FIG. 1 is a left side elevation showing my new design;
 FIG. 2 is a front elevation;
 FIG. 3 is a top plan view;

FIG. 4 is a top plan view with the case open and the scope stored therein;

FIG. 5 is a bottom plan view with the case closed and the scope mounted on the outside thereof; and,

FIG. 6 is a rear elevation.

I claim:

The ornamental design for a combination spotting scope, carrying case and stock therefor, as shown.
